DROP CABINET FOR SEWING MACHINES.

No. 431,207.

Patented July 1, 1890.

UNITED STATES PATENT OFFICE.

GEORGE L. GRAY, OF CHICAGO, ILLINOIS.

DROP-CABINET FOR SEWING-MACHINES.

SPECIFICATION forming part of Letters Patent No. 431,207, dated July 1, 1890.

Application filed September 13, 1889. Serial No. 323,805. (No model.)

To all whom it may concern:

Be it known that I, GEORGE L. GRAY, of Chicago, in the county of Cook and State of Illinois, have invented certain new and useful 5 Improvements in Drop-Cabinets for Sewing-Machines; and I do hereby declare that the following is a full, clear, and exact description thereof, reference being had to the accompanying drawings, and to the letters of 10 reference marked thereon, which form a part of this specification.

This invention relates to a novel construction in "drop-cabinets" for sewing-machines, and more particularly to improved devices 15 for securing the positive uplift into operative position of the leaf which supports the frame-arm or goose-neck of the machine.

The invention consists in the features of construction and combinations of parts hereinafter fully described, and pointed out in the 20 appended claims.

In the accompanying drawings, Figure 1 is a view in front elevation of a sewing-machine and cabinet constructed in accordance with 25 my invention. Fig. 2 is a fragmentary view, on an enlarged scale, in vertical longitudinal section on the line 2 2 of Fig. 3, of the upper part of the cabinet with the frame-arm or goose-neck removed, the part hereinafter described as the cover, for better illustration, being shown in a different section. Fig. 3 is a fragmentary view, on an enlarged scale, in vertical transverse section on the indirect line 3 3 of Fig. 2, of the parts shown in said 30 Fig. 2. Fig. 4 is a detail plan view illustrating the manner of connecting the lifting-strap with the swinging cover of the cabinet. Fig. 5 is a detail view illustrating the connection between the lifting-strap and supporting-leaf of 35 the cabinet. Fig. 6 illustrates a modified form of construction in the device for connecting the lifting-strap and swinging cover. Fig. 7 is a sectional plan view taken on a line passing through the pivots of the supporting-leaf, 40 showing a modified construction in the cross-bar for supporting the drive-belt when the supporting-leaf is dropped. Fig. 8 is a detail view of the under face of the top piece of the cabinet, illustrating the locking device for holding 45 the supporting-leaf in position.

In said drawings, A A indicate the sides

of the cabinet, A' the back thereof, and A² A² hinged doors for closing up the front of said cabinet.

A³ is a horizontal top piece resting upon 55 the sides and back of the cabinet. A leaf A, which supports the frame-arm or goose-neck A⁵ of the machine, fits within a suitable opening in the said top piece A³.

a a indicate depending arms attached to 60 the under face of the top piece and provided near their lower ends with bearing-apertures which register with similar apertures formed near the lower ends of other depending arms a' a', attached to the under face of 65 the leaf A⁴. A pivot rod or bar a² is passed through the said bearing-apertures in the arms a and a', and affords a hinged connection between the said leaf A⁴ and the top piece A³. The said frame-arm or goose-neck A is provided with a belt-pulley a³, of familiar construction, over which is trained a suitable 70 drive-belt a⁴. The said drive-belt a⁴ passes through openings in the leaf and is trained over a drive-pulley a⁵, supported in suitable 75 bearings upon the cabinet in a familiar manner. The said drive-belt a⁴ is located on the side of the pivot-rod a² remote from the free end of the dropping leaf, so that when the 80 said leaf swings downwardly within the cabinet the said belt will engage the rod and will be supported thereby, so that it will remain engaged with the pulleys a³ and a⁵. It is obvious that it is not necessary to employ the pivot-rod a² for supporting the belt in the 85 manner set forth, as other equivalent devices could be employed—such, for instance, as suitably-located arms or pins upon the cabinet. The free end of the leaf A⁴ in the particular construction illustrated is beveled 90 outwardly from top to bottom, as shown at a⁶, and the adjacent face of the top piece A³ is oppositely beveled, so that said parts will come in contact with each other when the upper surface of the leaf is flush with the upper surface of the top piece, whereby the said 95 leaf is prevented from passing over the said top piece. As a further means for limiting the upward movement of the leaf and to insure an unbroken surface with the top piece, a stop or lug a⁷ is secured to the under side 100 of the leaf and projects beyond the edge of

the same. Said stop a^4 is adapted to engage the under side of the top piece when the upper faces of the leaf and said top piece are flush with each other.

5 A⁶ is a trap or door hinged to the back A' of the cabinet and adapted to close a ventilating opening or window.

The devices herein shown for raising and lowering the leaf and attached goose-neck are 10 as follows: B is a cover hinged to the top piece A³ at the end of the latter opposite that with which the leaf is connected. Said cover is flat on its under face, while its upper face is preferably ornamented, so that when the machine is not in use and the goose-neck rests 15 within the cabinet said cover can be thrown over with its flat under face resting upon the top piece, and when so placed its ornamented upper face will give the cabinet the appearance 20 of a piece of furniture—such, for instance, as a desk or writing-stand. When the machine is in use and the cover is thrown outwardly, its flat surface, which is then uppermost, will serve the purpose of a table or extension-leaf. A 25 knob or projection a⁸, located upon the side of the cabinet, is preferably arranged to engage a suitable projection b upon the said cover. Said projections a⁸ and b are arranged to aid in sustaining the cover in a horizontal 30 position. I have illustrated the projection or stop b of the cover as one of the posts forming the ornamental part thereof; but it is obvious that any suitable part of or upon the cover can be used for this purpose.

35 C is a strap, rope, or other suitable flexible connecting-strand connected at one end with the cover B at a point between the ends thereof and passes through an opening in the top A³, and is connected at its opposite end 40 with the leaf A⁴.

C' is a plate-spring secured at one end to the under side of the leaf A⁴. The body portion of said spring is bent downwardly, so that it stands free from the leaf, and its free 45 end extends past the margin of the leaf and is located near the opening a⁹ in the top. As a convenient way of attaching to the said spring the strand C, (which in this instance has the form of a strap,) the free end of the 50 spring is bifurcated or forked, as shown at c in Fig. 1, and the strand or strap C passes through the slot in said forked end of the spring C'. C² C³ are stops or lugs located upon the strap C at a point below the spring, 55 said stops being shown as formed of separate pieces secured thereto. The said strand or strap C is made of such length and so arranged that when the cover B is thrown outwardly the leaf A⁴ will be lifted and brought 60 into position within the opening in the top before said cover reaches the outward limit of its movement, the spring of course yielding upwardly after the leaf has reached its normal position, so as to allow the cover to come into a horizontal position. By the use of 65 such spring therefor, or an equivalent yielding spring or resilient connection between

the strand and the parts to which it is attached, the bringing of the leaf to the full upward limit of its movement in every case is insured, it being obvious that in the absence of such spring yielding or resilient connection, the position of the leaf when raised would depend on the length of the strand or strap, and as it is practically impossible to prevent the strand or strap from stretching or contracting, or otherwise becoming changed in length, a strand or strap arranged as described cannot be relied upon to lift the leaf to its proper position unless such spring or flexible connection is present. The said spring or yielding connection may be made sufficiently stiff or strong enough to sustain the leaf during the use of the machine; but preferably a positive stop or locking device will be employed to hold the leaf in place after it has been lifted.

Devices are herein shown for automatically locking and sustaining the leaf A⁴ in its uplifted position, which comprise a stop or catch A⁷, having a yielding or spring extension a¹¹, which is secured to the side piece A adjacent to the free end of the said leaf. The said catch is provided with a rearwardly-extending pin a¹², projecting through an opening in the side piece A. A lug or projection b², arranged upon the cover B, is adapted to engage or abut against the pin a¹² when said cover is swung outwardly. I have shown said lug b² as arranged upon a post b on the cover; but it is obvious that it can be otherwise located. It will be seen that when the said cover is swung outwardly and brings the leaf A⁴ to its uplifted position the lug b² will engage the pin a¹² and press the catch A⁷ inwardly beneath the edge of the leaf, the stop a⁷ on said leaf having a slot cut therein for the admission of said catch.

D is a convenient form of clip or fastening device for connecting a strap C with the cover B. Said clip consists of a recessed plate D', provided with marginal flanges D² for attaching it to the cover, and with a tongue d, overhanging the bottom of the recess parallel with the same. Said plate is located within a recess formed in the cover, so that the upper face of the flanges thereof will be flush with the surface of said cover. The end of the strap C is attached to the plate D by being bent over and inserted beneath the tongue d and held by a screw d', which passes through the said tongue, the end of the strap, and the bottom of the plate. The top or outer face of said tongue d is arranged below the top of the flange, so that when the strap is attached to the plate, as described, and carried over the tongue in the manner shown said strap will not project above the face of the cover B. The strap lies in a groove b' in the cover and in a groove a¹⁰ in the top A³, so that its upper surface is flush with said parts when the cover is open.

The operation is as follows: For example, it will be assumed that the parts are in the

position shown in full lines in Fig. 1—that is to say, the machine ready for use. To close the cabinet the cover B is thrown inwardly.

This movement of the cover allows the catch

5 A⁷ to spring back from engagement with the leaf, loosens the strap, and also allows the leaf and goose-neck to swing downwardly within the cabinet. It is obvious that when the said goose-neck swings downwardly the 10 pulley a³, supporting the belt, will move over the pivot-rod a² to the opposite side of the latter, and the said rod a² will engage said belt and prevent the same from loosening and slipping off of the pulleys. When it is 15 desired to use the machine, the cover B is swung outwardly upon its hinges. As the said cover swings outwardly it carries the strap C with it, and the said strap acts upon the end of the spring C' so as to raise said leaf into working position. When the cover is swung outwardly, no force is required to bring the leaf into position, as the said cover will fall by its 20 own weight until it is horizontal, whereupon the stop a⁸ will prevent a further movement 25 thereof, and the lug b², engaging the pin a¹², will press the catch inwardly beneath the leaf, and thereby sustain the same.

The door A⁶, before referred to, is adapted to be opened or closed by the movement of 30 the supporting-leaf. A convenient way of securing such movement is to extend the strand or strap beyond the end of the spring C' and connect it to the free end of said door, and I have so shown it in the drawings.

35 Fig. 6 illustrates a modified form of construction in the elastic connection of the strap with the parts to which it is attached. In this form of the device the strap C is rigidly attached to the leaf, but has yielding connection with the cover B. E is a coiled spring located within a longitudinal recess E' formed in the cover. The said spring is attached at one end to the said cover, and at its opposite end to the strap C. The said spring is of the 40 same relative strength as the spring C' and acts in the same manner.

In Fig. 7 is shown a modified form of construction embodying my invention. In said figure, A indicates one of the side pieces of 50 the cabinet-frame, and a and a' indicate the arms depending from the cover A⁴ and top A³, said arms being connected by pivots a²a². F indicates a cross-piece or support having bent ends attached to the side pieces A in 55 such a manner as to bring the cross-piece F in line with the pivots. a⁴a⁴ is the drive-belt, which is located on the side of the said cross-piece remote from the free end of the dropping leaf. It is obvious that said cross-piece will sustain the belt upon the pulleys 60 as the leaf swings downwardly.

In Fig. 8 is shown a modified form of construction in the devices for locking the leaf A⁴ when the same is lifted. A button A⁸ is 65 pivoted to the under surface of the top A³ in position to swing under the edge of the leaf.

Such button is turned by hand after the cover has been turned back and the leaf lifted, so as to hold the leaf positively in place.

The advantages of the construction herein 70 described will be plainly seen. Heretofore it has been a difficult matter to secure the uplift of the leaf in this class of devices into its exact position, for the reason that unless the connecting-piece between the cover and the 75 leaf was of the exact length required the leaf would not be brought to its operative position, or if it was the right length the strain upon the said connecting-piece would soon stretch it and make necessary another adjustment of the same. In the construction herein described it is not necessary to obtain an exact adjustment of the connecting piece or strand, but only such as will bring the leaf into or near its uplifted position when the 80 swinging cover is near the outward limit of its movement, whereby by a further movement of said cover the spring will be brought into action to raise the said leaf into the same 85 plane with the top of the cabinet. 90

I claim as my invention—

1. A drop-cabinet for sewing-machines, comprising a hinged supporting-leaf, a hinged cover for operating said supporting-leaf, and a resilient connection between said supporting-leaf and cover, substantially as described. 95

2. A drop-cabinet for sewing-machines, comprising a hinged supporting-leaf, a hinged cover for operating said supporting-leaf, a connecting strand or strap connected at one 100 end with one of said parts, and a spring interposed between the other end of said strand or strap and the other of said parts, substantially as described.

3. A drop-cabinet for sewing-machines, 105 comprising a hinged supporting-leaf, a hinged cover for operating said supporting-leaf, a connecting strand or strap attached to said cover, and a leaf-spring secured to said supporting-leaf and connected with said strand 110 or strap, substantially as described.

4. In a drop-cabinet for sewing-machines, the combination, with the cabinet-frame and hinged supporting-leaf, a goose-neck or frame-arm upon said supporting-leaf, drive-pulleys located, respectively, upon said frame-arm and upon the cabinet-frame, and a drive-belt trained over said pulleys, of a stationary cross-bar or support located upon the cabinet-frame at right angles to the path of 120 said supporting-leaf and substantially in alignment with the axis thereof, whereby said cross-bar or support is adapted to sustain said drive-belt upon the pulleys when the supporting-leaf is dropped within the cabinet, substantially as described. 125

5. In a drop-cabinet for sewing-machines, the combination, with the cabinet-frame, a hinged supporting-leaf, and a hinged cover connected with and actuating the said leaf, 130 of a catch upon said cabinet-frame for engagement with said leaf when at the upward

limit of its movement, said catch being located in the path of and actuated by said hinged cover, substantially as described.

6. In a drop-cabinet for sewing-machines, the combination, with the cabinet-frame, a hinged supporting-leaf, and a hinged cover connected with and actuating said leaf, of a spring-catch upon said cabinet-frame for engagement with said leaf when at the upward limit of its movement, said spring-catch being located in the path of and actuated by said cover, substantially as described.

7. In a drop-cabinet for sewing-machines, the combination, with the cabinet-frame and hinged supporting-leaf and a hinged cover connected with and actuating said leaf, of a

spring-catch upon said cabinet-frame for engagement with said leaf when at the upward limit of its movement, and a pin or projection upon said catch which projects through the cabinet-frame and is located in the path of said hinged cover, said cover being adapted to engage and actuate said pin and catch, substantially as described.

In testimony that I claim the foregoing as my invention I affix my signature in presence of two witnesses.

GEORGE L. GRAY.
